UNITED STATES PATENT OFFICE.

HENRY LEMMERMAN, OF HASBROUCK HEIGHTS, NEW JERSEY.

DESIGN FOR A BOTTLE.

SPECIFICATION forming part of Design No. 26,482, dated January 5, 1897.

Application filed November 14, 1896. Serial No. 612,160. Term of patent 14 years.

To all whom it may concern:

Be it known that I, HENRY LEMMERMAN, a citizen of the United States, residing at Hasbrouck Heights, in the county of Bergen, in the State of New Jersey, have invented a certain new and original Design for Bottles, of which the following is a specification, reference being had to the accompanying drawings, forming a part hereof.

- o Figure 1 of the drawings represents a side view of a bottle which embodies my design. Fig. 2 is a top plan view of the bottle shown in Fig. 1.

My invention relates particularly to the upper part or neck of a bottle, which, in accordance with my design, has its terminal portion disposed with the axis thereof substantially at a right angle with the axis of that portion thereof which is next to the body of the bottle, the mouth of the bottle being in a plane substantially parallel with the axis of the last-mentioned portion of the neck.

Referring particularly to the drawings, it will be seen that from the body A of the bottle the neck a rises in a direction substantially parallel with the axis of the body A. The portion a of the neck is joined by a curved portion a' of about ninety degrees with the terminal portion a², which is disposed with its axis substantially at a right angle with the portion a of the neck and with the mouth opening toward a plane substantially at right angles with the axis of the portion a of the neck.

What I claim, and desire to secure by Letters Patent, is—

The design for a bottle substantially as shown and described.

This specification signed and witnessed this 23d day of October, A. D. 1896.

HENRY LEMMERMAN.

In presence of—

ALFRED W. KIDDLE,
W. B. GREELEY.
